UNITED STATES PATENT OFFICE

OSCAR ROESEN, OF NEW YORK, N. Y., ASSIGNOR TO ROBERT HOE, OF NEW YORK, N. Y.

DELIVERY MECHANISM FOR PRINTING-MACHINES.

SPECIFICATION forming part of Letters Patent No. 782,924, dated February 21, 1905.

Application filed April 16, 1904. Serial No. 203,438.

To all whom it may concern:

Be it known that I, OSCAR ROESEN, a citizen of the United States, residing at New York, county of New York, and State of New York, have invented certain new and useful Improvements in Delivery Mechanisms for Printing-Machines, fully described and represented in the following specification and the accompanying drawings, forming a part of the same.

10 This invention relates to certain improvements in delivery mechanisms for printing-machines.

In fast printing-machines—such, for instance, as a machine of the rotary type now employed for web-printing—it is customary to deliver the sheets cut by the usual cutting-cylinders or other mechanism to cylinders, usually collecting-cylinders, on which the sheets are held by pins on their cylinders. In 15 certain classes of printing, however, the use of pins is objectionable because of the perforations left thereby in the margins of the sheets. It is furthermore desirable in certain 20 classes of printing to deliver sheets unfolded and to do this in a manner which avoids smutting or offsetting, this being particularly desirable in machines where heavy cutwork is being printed.

It is one of the objects of the invention to 25 produce an improved delivery mechanism for web-printing machines in which the separated sheets are carried forward by grippers and delivered in an unfolded condition, the gripper mechanism running at the speed of the web, so that no acceleration of the sheets after cutting is necessary.

A further object of the invention is to produce an improved delivery for web-printing machines employing sheet-carriage mechanism whereby the sheets are delivered flat and without danger of smutting.

40 A further object of the invention is to produce an improved delivery for web-printing machines in which the webs are taken by a collecting mechanism employing grippers and after cutting are forwarded, the mechanism running at the speed of the web and including a plurality of sheet-taking devices, where-

by the sheets are alternately sent in different directions and delivered unfolded.

50 A further object of the invention is to produce an improved delivery mechanism for web-printing machines employing collecting-cylinders provided with grippers, successive sheets being taken by the cylinders alternately 55 and the collected sheets being delivered in an unfolded condition by a carriage-delivery mechanism.

With this and other objects in view not specifically hereinbefore pointed out the invention consists in certain constructions and in certain parts, improvements, and combinations, as will be hereinafter described and then more particularly set forth in the claims 60 hereunto appended.

65 Referring to the drawings, which form a part of this specification, and in which like characters of reference indicate the same parts, Figure 1 represents in side elevation so much of the delivery mechanism of a printing-machine 70 as is necessary for an understanding of the invention. Fig. 2 is a sectional elevation on lines 2 2 of Fig. 1.

In the drawings, which represent a preferred embodiment of the invention, 1 indicates a frame in which the operating parts of the mechanism are supported, the frame being of any suitable form and construction. The printing mechanism is not herein illustrated, a description thereof not being necessary for an understanding of the invention; but it may consist of a rotary printing couple or couples of any approved type.

75 The printed web indicated at W is forwarded by guides of any approved type—as, for instance, rollers 2—to the cutting mechanism, which may be of any desired construction. In the particular construction illustrated this cutting mechanism embodies the usual cutting-cylinders 3 4, said cylinders being mounted 80 upon shafts 5 6 and driven by gearing which will be hereinafter referred to. If desired, a slitter 8 may be employed, as is usual in such constructions.

85 The mechanism for forwarding the sheets 90 after they have passed the cutting-cylinders

may be widely varied in construction; but it will include grippers which run at the surface speed of the web. Preferably, furthermore, these grippers will be so mounted as to form 5 parts of a collecting mechanism. The particular construction by which the grippers are mounted, so that they may act to collect sheets, may be widely varied. As shown, two cylinders 9 10 are employed, these cylinders 10 being mounted on shafts 11 12, suitably supported in the frame. The cylinder 9 carries grippers 13, which may be of any usual type. Similarly the cylinder 10 carries grippers 14. In the operation of the mechanism the forward edge of the web issuing from the cylinders 3 4 is taken by one of the sets of grippers—as, for instance, the grippers 13—and carried onward, the cutting mechanism operating as usual after the forward edge of the 20 sheet has been taken by the grippers. After cutting, the forward edge of the web, formed by cutting off the web, is taken by the grippers 14, and when the cylinders referred to are, as they preferably will be, collecting-cylinders, this operation proceeds, successive sheets being taken by the cylinders alternately until the required collection is completed.

The cylinders may be driven in any suitable 30 manner. As shown, there is provided a way-shaft 15, said shaft carrying a miter-gear 16, which meshes with a miter 17, mounted on the shaft 18, running across the machine. This shaft 18 is provided with a gear 10', which 35 meshes with the lower one of a pair of intermediates 20 21. The upper intermediate 21 is in mesh with a gear 22 on the shaft 12 of the cylinder 10, this gear 22 being in mesh with the gear 23, mounted on the shaft 11 of 40 the cylinder 9. An intermediate 24 serves to drive one of the cutting-cylinders, these being intergeared in any usual manner.

While the sheets might be delivered, whether 45 collected or not, from the gripper-carrying mechanism in various ways, they will preferably be delivered by carriage mechanisms of the type usually employed with machines of the type known in the art as "two-revolution cylinder-machines." The particular type of 50 carriage mechanism employed may be widely varied. The one selected for the purpose of illustrating the invention corresponds in its essential characteristics to the construction illustrated in Patent No. 591,223, dated October 5, 1897. In the preferred construction 55 two carriages will be employed, one for each collecting mechanism. As shown, the frame is provided with ways 25, in which travel rollers 26, these rollers serving, through suitable means, to support side frame-pieces 27. These frame-pieces are connected at their forward ends by a rod 28 and also serve to support a roller 29. Mounted in the frame is a rod 30, said rod serving to support fingers 31,

on which the sheets are received when the 65 carriage is in receiving position. The rod 28 carries a series of lever-arms 32, in which are mounted rollers 33. The carriages and carriage-operating mechanisms are duplicates and therefore only one is shown and described. The presence of the second carriage is indicated, however, by a part of a driving mechanism therefor. (See Fig. 1.)

The means for reciprocating the carriages may be varied widely. As shown, the shaft 75 15, before referred to, is provided with worms 34, these worms meshing with the worm-gears 35, carried by the shafts 36, extending across the machine. These shafts have secured to them crank-arms 37, which are connected by links 38 to two sectors 39, pivoted at 40 to the frame of the machine. Each of the sectors, of which only one is shown, is in mesh with a gear 41, mounted on a shaft 42, extending across the machine, this shaft being 85 carried in brackets 43, secured to the frame. The shafts 42 also carry gears 44, which are in mesh with racks 45 on the carriages. It will be understood that as the crank-arms rotate the sectors are reciprocated, and the 90 gears 44, being driven in opposite directions, serve to reciprocate the carriage.

Means are preferably employed to insure the stripping of the sheets from the collecting-cylinders. While this means may vary in 95 construction, as shown, strippers 46 are employed, these strippers being carried on shafts 47, extending across the machine. These shafts are provided with crank-arms 48, which are connected to cam-rods 49, the other 100 ends of these rods being forked, as at 50, and carrying rolls 51, which coöperate with cams 52; the construction being the usual one. Preferably, also, delivery-tapes 53 will be employed, these tapes being supported and 105 driven in the usual manner. The crank-arms 37 are so set that when one of the carriages is in receiving position the other one will be either in delivery position or intermediate the delivery and receiving position, according to 110 the number of sheets to be collected. When one of the carriages comes into its receiving position, the stripper 46 is thrown in and the stripper, in connection with the tapes 53, causes the sheets to be delivered to the supporting-fingers of the carriages. The gear 41 is then operated in the reverse direction 115 and the carriage is moved outward to its delivery position. As the carriage starts on its rearward movement the roll 29 is operated by 120 a clutch mechanism not necessary to describe herein, but which is fully described in the patent before referred to, and the pack of 125 sheets are fed forward and delivered to any suitable receiver.

The receiver employed may be widely varied in construction. As shown, it consists of a table 54, mounted on sprocket-chains 55,

these chains passing over sprocket-wheels 56, mounted on short shafts 57, supported in bearings 58 on the frame and over sprocket-wheels 59, carried on a shaft 60, this shaft being suitably supported in the frame. This shaft 60 is provided with a worm-wheel 61, which is in mesh with a worm 62, mounted on a shaft 63, which may be driven in any suitable manner. As shown, a pawl-carrier 64 is mounted on this shaft, this pawl-carrier being operated by a link 65 from the cam 66 on the shaft 36, before referred to. With this construction the table is lowered as successive sheet collections are deposited thereon, and after a table is filled a second one may be mounted in the chains to receive the sheets, the second one being filled as the first one is removed.

Suitable joggers may be employed, if desired, to even up the pile of sheets. In the construction shown side jogger-arms 67 are employed, these jogger-arms being mounted on shafts 68. End jogger-arms 69 operate on one end of the pile of sheets, these arms being mounted on shaft 70. This shaft 70 is driven by link 71 from the sector before described, intermediate driving means of any suitable character being employed between the shafts 68 and 70. Additional side joggers 72 are also shown, these joggers being mounted on the shaft 73, which is driven by a link connection 74 from the shaft 68.

The operation of the construction will be clearly understood from the foregoing description. A specific statement thereof is therefore unnecessary. It will be seen that by the construction before described grippers may be employed which take successive sheets at the speed of the web, and, furthermore, by the use of collecting-cylinders and by duplicating the sets of carriages the speed at which the carriage is moved is lowered to a degree which makes it practicable to use this form of de-

livery in connection with web-printing machines.

Changes and variations may be made in the mechanism by which the invention is carried into effect, and it is also to be understood that certain features of the construction in which the invention is embodied may be used independently of other features without departing from the invention. The invention is not to be limited, therefore, to the specific construction hereinbefore described, and illustrated in the accompanying drawings.

What is claimed is—

55

1. The combination with means for forwarding a web, of means for cutting sheets therefrom, devices whereby alternate sheets in an unfolded condition may be forwarded in different directions, and a pair of delivery-carriages operating to deliver the sheets unfolded, substantially as described.

2. The combination with means for forwarding a web, of means for cutting sheets therefrom, collecting mechanisms to which alternate unfolded sheets are delivered, and delivery-carriages coöperating with the collecting mechanisms and delivering the collected products unfolded, substantially as described.

3. The combination with means for forwarding a web, of means for cutting sheets therefrom, collecting-cylinders to which alternate unfolded sheets are delivered, and a pair of delivery-carriages coöperating with the cylinders and operating to deliver the collected product unfolded, substantially as described.
